CALIBRATED SPRING SCALE

Dana W. Mox, Glenview, Ill., assignor to Hanson Scale
Company, Northbrook, Ill., a corporation of Illinois

Filed Apr. 9, 1964, Ser. No. 79,431

Term of patent 14 years

(Cl. D52—10)

FIG. 1

FIG. 2

FIG. 3

FIG. 4

FIG. 5

FIGURE 1 is a front elevational view of a calibrated spring scale embodying my new design;

FIGURE 2 is a side elevational view, the other side being a mirror image thereof;

FIGURE 3 is a back elevational view;

FIGURE 4 is a top plan view; and

FIGURE 5 is a bottom plan view.

I claim:

The ornamental design for a calibrated spring scale, as shown and described.
